UNITED STATES PATENT OFFICE

PETER L. MIKESKA, OF SCHENECTADY, NEW YORK, ASSIGNOR TO GENERAL ELECTRIC COMPANY, A CORPORATION OF NEW YORK

DESIGN FOR AN OIL BURNER FURNACE

Application filed August 9, 1932. Serial No. 44,580. Term of patent 14 years.

To all whom it may concern:

Be it known that I, PETER L. MIKESKA, a citizen of the United States, residing at Schenectady, in the county of Schenectady, State of New York, have invented a new, original, and ornamental Design for an Oil Burner Furnace, of which the following is a specification, reference being had to the accompanying drawing, forming a part thereof.

Fig. 1 is a perspective view of the front of an oil burner furnace embodying my new de-

sign and Fig. 2 is a perspective view of the side of an oil burner furnace embodying my new design. Fig. 3 shows a plan view of an oil burner furnace embodying my new design.

I claim:

The ornamental design for an oil burner furnace substantially as shown.

In witness whereof, I have hereunto set my hand this fifth day of August, 1932.

PETER L. MIKESKA.
